CLAIM

The ornamental design for a cup with handle, as shown and described.

DESCRIPTION

FIG. 1 is a top perspective view of my new design for a cup with handle;

FIG. 2 is front elevation view thereof;

FIG. 3 is a top plan view thereof;

FIG. 4 is a cross-sectional view thereof, taken about line 4-4 of FIG. 3; and,

FIG. 5 is an enlarged detail of a portion of FIG. 2.

The portions of the cup with the handle shown in broken lines form no part of the claimed design. The broken line circles in FIGS. 2 and 5 show partial view indicia and form no part of the claimed design. The broken line arrows in FIG. 3 show cross-sectional indicia and form no part of the claimed design.
